UNITED STATES PATENT OFFICE

EUGENE A. HOLMGREEN, OF SAN ANTONIO, TEXAS

COTTON TRAMPER

Application filed August 4, 1928. Serial No. 297,490.

This invention relates to improvements in packing or tramping machines, and more particularly to cotton trampers for use in baling cotton. The invention consists in certain improvements in the mechanism for operating the trumper, whereby a rigid machine is provided. In trampers now in use a series of chains carrying crank pins is provided through which a reciprocating movement is secured by the pins traveling with the chain. This construction results in great uncertainty in the alignment and action of the pins and their connections. My construction aids to correct this uncertainty by introducing a positive moving connection that will always function in a straight line, and hence not be subject to uncertain movements.

Referring to the accompanying drawings, which are made a part hereof and on which similar reference characters indicate similar parts,

Figure 1 is a side elevation of my trumper,

Figure 2 is a plan view partly in section, the section being taken on line 2—2 of Fig. 1,

Figure 3 is a vertical section showing the trumper and operating connection,

Figure 4 is an end elevation looking toward the left of Fig. 1,

Figure 5, a partial plan view with the trumper beam shown in section, and

Figure 6 is a view similar to Fig. 5, of a modified form.

My device is mounted upon two parallel beams 10 and 11, preferably of steel or cast iron, held together by suitable cross braces. Supporting standards 12 and 13 are mounted in a vertical position upon the base and are held in an upright position by braces 14 and 15. The upright members 12 and 13 provide guides for the reciprocating cross head which operates the trumper or packer. These guides consist of rods which have reduced threaded ends, the lower end passing through a flange in the beams and having nuts 16 thereon and the upper end passing into and through a top casting 17 and having nuts 18 thereon. The standards 12 and 13 have steel lugs 19 and 20 welded near the upper ends, or otherwise secured thereto. The supporting braces 14 and 15 are hollow

and have rods 21 extending therethrough. Nuts 22 and 23 secured on the ends of the rods hold the supporting braces 14 and 15 in position. The lower end of the braces 14 and 15 preferably seat in sockets 24 in lugs which are welded to the top of the beams 10 and 11. This structure provides a rigid support for the standards which carry the packer. The supporting beams 10 and 11 have bearings 25, 26 and 27 welded thereon, or otherwise secured. These bearings carry shafts 28, 29 and 30. Upon these shafts are secured driving gears 31, 32 and 33. Upon the outer end of the shaft 28 is mounted a pulley 34 or other suitable means for receiving power from an engine or other suitable source of power, not shown. The gear wheels 33 have crank pins 35. These crank pins carry one end of connecting rods 36 and 37. The connecting rods are held upon the crank pins by bolts 38 which pass through the crank pins and secure thereon washers 39. The connecting rod bearing is composed of two members 40 and 41. These members are held together by the long U-bolts or otherwise, which pass around cross head pins 62 and 63 on the cross head 43. This cross head carries castings 44 and 45 which slide upon the guides 12 and 13. The castings also have lugs 46 and 47 which provide bearings for a shaft 48 carrying a guide roller 49. The cross head also carries a pinion 50 mounted upon a shaft 51. A standing beam or rack 52 is secured upon a cross brace on the beams 10 and 11. This standing beam has a series of bars 53 secured in holes in the flanges of the beam. These bars provide a rack on one side of the beam which is engaged by the teeth on the pinion 50. The trumper 54 is made of a beam similar to the standing rack beam 52, and has rods 55 secured in the flanges on the beam corresponding to those on the standing beam 52. The lower end of the trumper beam 54 has a rectangular block 56 secured thereupon, and this rectangular block has slats 57 secured on its under side. Secured to the under side of the beams 10 and 11 are brackets 58 and 59. These brackets engage the flanges of the beam 54 and guide it during reciprocation. The casting 17 has bolts 60 and 61 threaded

therethrough, the nuts 60' and 61' allowing an endwise adjustment of the bolts. The bolts 60 and 61 are preferably welded to the outer flanges on the upper end of the standing beam 52. Obviously these bolts could be secured to the flanges of the beam by bolts or other fastening devices.

In Figure 6 is shown a modified form of pinion which forms the driving connection between the cross head and the trumper. This form provides means for varying the length of the trumper stroke. In this form, instead of the pinion 50, I use a pinion 64 which meshes with the bars on the beam 52 only. On the outer ends of the shaft which carries the pinion 64 I mount pinions of a larger diameter which mesh with bars 66 extending beyond the outer sides of the flanges on the beam 54. Vertical movement of the cross head in this form will move the trumper through a distance somewhat greater than twice that through which the pinion 64 moves. By changing the relative size of pinions 64 and 65 the length of the stroke of the trumper may be regulated as desired.

If desired, the pinion 65 may engage the stationary beam and the pinion 64 the trumper beam so that the trumper stroke will be less than double the stroke of the cross head.

The operation of the device is as follows: Power is applied to the pulley 34 which drives the shaft 28, and through the medium of gears 31, 32 and 33 the connecting rods 36 are reciprocated, and in turn they reciprocate cross head 43. The pinion 50 rotatably secured on a shaft through the cross head engages the racks 53 and 55 on the stationary beam 52 and the movable beam 54 respectively. Since the beam 52 cannot move, vertical movement of the cross head will rotate the pinion 50 to move the trumper beam 54 vertically through a distance twice that through which the cross head travels. By using the form shown in Fig. 6, the trumper may be caused to move through a distance more or less than twice that through which the cross head travels. The roller 49 engages between the flanges on the rear side of the trumper beam 54 and holds it in position. Lugs 58 and 59 guide the lower end of the trumper beam during its vertical reciprocation. The U-bolts 42 which pass around the upper end of the crank pins 62 and 63 take the strain off the bearing members 40 and 41 and distribute it between the two crank pins. The U-bolts 42 also carry some of the strain which otherwise would be put upon the connecting rods 36 and 37.

While I have shown and described my invention as applied to a cotton trumper, it should be apparent that it need not be limited to this use. It may find utility in devices where specially long strokes of a plunger are desired with a short stroke op-

erating plunger, such for example as the piston or plunger in a cylinder. Among possible fields of utility would be as a hay press or a pumping jack for raising water, oil or other liquid, since the tendency in modern practice now is toward longer strokes in machines of this character. By the use of my device the stroke of the pump piston may be double or more or less that of the piston on the steam cylinder.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. A trumper comprising a base, posts vertically mounted upon said base, a stationary beam mounted vertically upon said base and secured at its upper end to the upper end of the said posts, a cross head mounted for vertical reciprocation upon said posts, a trumper beam having rack teeth on one side positioned in guides upon said base, a guide roller upon said cross head engageable by said trumper beam, the said cross head having a pinion engaging the teeth of the trumper beam on one side and having the other side engaging rack teeth on the said stationary beam, a plurality of gears rotatably mounted upon said base, a connecting rod secured to a crank pin on one of said gears and to a pin on the said cross head, and means for rotating the said gears to vertically reciprocate the said cross head and the said trumper, substantially as set forth.

2. A cotton trumper comprising a base, a driving shaft and a driven shaft mounted upon said base, a pinion mounted upon the driven shaft, idle pinions forming driving connection between the driving shaft and the driven shaft, a plunger mounted for vertical reciprocation, a pair of posts vertically mounted upon the said base, a pair of I-beams having racks on their inner sides one of said I-beams being rigidly mounted upon the said base and the other having a trumper shoe on its lower end and being mounted for vertical reciprocation, a pinion positioned to have its opposite sides in engagement with the racks on the I-beam, a piston rod connecting the last named pinion with the pinion on the driven shaft, substantially as set forth.

3. A cotton trumper comprising a base, vertical guide posts mounted upon the base, supporting braces for the guide posts, a cross head mounted to slide upon the posts, a trumper mounted for vertical reciprocation between the posts, an I-beam vertically mounted upon the base, the said I-beam having bars secured in its flanges along one side to provide a rack, a second I-beam secured

to the tramper and secured to permit vertical reciprocation this I-beam having bars secured in its flanges to provide a rack corresponding to the rack in the first named I-beam, a pinion mounted between the I-beams having its teeth in engagement with the racks on each beam, a driving and a driven shaft rotatably mounted in the said base, a pinion on the driven shaft, a piston connecting the pinion on the driven shaft with the pinion between the I-beams, and driving connection between the driving shaft and the pinion on the driven shaft, substantially as set forth.

4. A tramper comprising a base, posts mounted upon the base, supporting braces for securing the posts in a vertical position, a beam vertically mounted upon the said base, said beam having a series of racks on one side, a cross head mounted for vertical reciprocation between the said posts, a second beam having a tramper mounted upon its lower end the said beam having rack bars on one side, a pinion mounted upon the said cross head between the said beams and having its teeth in engagement with the racks on the said beams, and means for reciprocating the said cross head whereby the pinion between the said beams will move the tramper through a distance greater than that through which the pinion moves, substantially as set forth.

5. A tramper comprising a base, posts vertically mounted upon said base, a stationary beam mounted vertically upon said base and secured at its upper end to the upper end of the said posts, a cross head mounted for vertical reciprocation upon said posts, a tramper beam having rack teeth on one side positioned in guides upon said base, the said cross head having a pinion engaging the teeth of the stationary beam on one side and being operatively connected to rack teeth on the said tramper beam, a plurality of gears rotatably mounted upon said base, a connecting rod secured to a crank pin on one of said gears and to a pin on the said cross head, and means for rotating the said gears to vertically reciprocate the cross head and the said tramper beam, substantially as set forth.

In witness whereof, I have hereunto set my hand at San Antonio, Texas, this 23d day of July, A. D. nineteen hundred and twenty-eight.

EUGENE A. HOLMGREEN.
